Atty's.*

UNITED STATES PATENT OFFICE.

CHARLES W. WILSON, OF YORK, PENNSYLVANIA.

MASK FOR MAKING PHOTOGRAPHIC PRINTS.

1,247,051.

Specification of Letters Patent.

Patented Nov. 20, 1917.

Application filed March 21, 1917. Serial No. 156,435.

To all whom it may concern:

Be it known that I, CHARLES W. WILSON, a citizen of the United States, and resident of York, Pennsylvania, have invented certain new and useful Improvements in Masks for Making Photographic Prints, of which the following is a specification.

My invention consists of a mask for defining the field which will be printed upon a sensitized photographic paper and for defining a border portion surrounding the said field having thereon border marks or lines which will not only act as guides in trimming the sheets but will enable the customer to choose any one of a number of borders which may be preserved in the trimming, thus rendering it possible to cater to the various tastes of customers.

In carrying out my invention I provide the mask with means whereby guiding marks may be made on the prints beyond the margins surrounding the field, which marks will enable the photographer to trim the print in any one of a number of ways

25 to suit the taste of the customer, the marks being disposed in a novel relation so that although they act as guides for trimming they are so located as to render possible the choice by the customers of different borders.

30 I am aware that masks have been disclosed prior to my invention for exposing a definite size of field to be printed on the sensitized paper and to print or provide in the printing process guiding marks adjacent the corners of the field for trimming as in Letters Patent of the United States, Nos. 1,060,618, and 1,061,727.

In the drawings;

Figure 1 is a view of the mask.

40 Fig. 2 is a view of a print made from the mask, this print not being trimmed.

Fig. 3 represents the print trimmed according to one of the designs from which a choice may be made.

45 Figs. 4 to 7 represent the print but with different styles of borders, all of which may be made by following either one of the several guides or indicating lines or marks made on the print through the mask when

50 the print is being made from the negative in the ordinary way.

Fig. 8 shows the corner of a print provided with ornamental border lines.

In carrying out the invention I may use 55 as the material of the mask celluloid or glass. It is provided with a portion 1 trans-

parent or open for the passage of the light and having surrounding this open or transparent field portion a light resisting portion, indicated at 2. Surrounding the portion 1 and spaced apart therefrom by an intervening light resisting section 3 of the light resisting body 2 I provide a border marking 4, which may consist of a continuous line, as shown, or this marking may be of any suitable design, character, such as fine scroll-work or the like. This border marking will permit the passage of the light and produce a border on the print when this is developed. I also provide a second border marking 5 separated from the first by an intervening portion 6 of the light resisting body and this second border marking may be a continuous line like that first described, or it also may be of any desired design, such as scroll-work or a curved line or lines.

Any desired number of these border markings may be employed but I have found that two such markings will answer all requirements.

55 In the light resisting body or portion 2 I also provide guide markings shown at 7. These being out beyond the border markings and separated therefrom by intervening opaque or light resisting parts of the light resisting portion 2, these intervening parts being indicated at 8. These guide markings will be printed on the paper when the mask is applied thereto between the negative and the sensitized surface of the paper and they will serve for guidance in the trimming of the print.

60 It will be noted that these markings are in line with the border markings, though separated or spaced therefrom and out beyond them, each marking being in line with one of the border lines or markings and there are twice as many guide markings at each corner as there are border markings surrounding the transparent fields 1. The border markings may be continuous to extend entirely around the open field 1 or they may extend only part way around, as the taste of the photographer or customers may dictate.

65 The print resulting from the use of this mask may be trimmed to present any one of a plurality or series of border effects.

Fig. 2 illustrates the print resulting from the use of the mask before any trimming is done.

70 Fig. 3 illustrates one form of trim in

which the print is cut away in line with the inner ends of the guide markings. This will leave a narrow margin 9 beyond the second or outer border line and between it and the 5 edge of the print or sheet.

Fig. 4 shows another style of print resulting from trimming along the outer border line but leaving said border line on the paper at the extreme margin of the print.

10 Fig. 5 illustrates another method of trimming by which a white margin is left between the inner border line and the edge of the paper, the outer border line having been trimmed away along its inner edge.

15 Fig. 6 illustrates another form of trimming in which the inner border line is left on the print while the margin outside of this border line is trimmed away.

Fig. 7 illustrates a further style of print 20 resulting from trimming along the inner edge of the inner border line so that this will be trimmed away entirely leaving a white margin between the picture field and edge of the paper.

25 By these several forms of trims the photographer can suit the tastes of various customers. The border lines together with the guide markings will enable the trimming to be done with ordinary shears or the usual 30 form of cutter may be employed, such as shown in the patents above referred to.

I may employ as the mask a plate of glass sheet material as celluloid having the border and guide markings together with the 35 opaque field provided thereon in any suitable way.

Instead of having the center 1 of transparent material an opening may be formed here and instead of making the border of 40 transparent markings parts may be cut out from the material of the mask to provide this border marking.

It will be understood that instead of celluloid or glass the mask may be made of any 45 suitable material as paper.

What I claim is:

1. A photographic mask having a central portion or field for the passage of light surrounded by a light resisting portion and

transparent border marks in said light resisting portion with transparent guide marks adjacent the corners and out beyond the border markings and separated therefrom by an intervening part of the light resisting portion of the mask, substantially as 55 described.

2. A photographic mask having a central portion or field for the passage of light surrounded by a light resisting portion and transparent border markings in said resisting portion substantially continuous and surrounding the field with transparent guide producing marks at the corners of and out beyond said border and separated therefrom by an intervening part of the light resisting 60 portion of the mask, substantially as described.

3. A photographic mask having a central portion or field for the passage of light surrounded by a light resisting portion and 70 transparent border marks in said light resisting portion with transparent guide marks adjacent the corners and out beyond the border markings and separated therefrom by an intervening part of the light resisting 75 portion of the mask, said guiding marks being at right angles to each other at the corners and in line respectively with the adjacent border marks, substantially as described.

4. A photographic mask having a central portion or field for the passage of light and a light resisting portion surrounding said field with a plurality of markings or borders for the passage of the light arranged in said 8 light resisting portion and at different distances from the field with guide marks separated from and out beyond the border markings and adjacent the corners thereof, there being twice the number of such guide markings at the corners as border markings and said guide markings being in line with the border markings respectively, substantially as described.

In testimony whereof, I affix my signature.
CHAS. W. WILSON.

Witness:
NOAH C. MAY.
